UNITED STATES PATENT OFFICE

2,026,345

IRONING MACHINE

Rudolph W. Janda, Berwyn, Ill., assignor to Con-
Ion Corporation, Cicero, Ill., a corporation of
Illinois

Application September 15, 1933, Serial No. 689,534

12 Claims. (Cl. 68—9)

This invention relates to ironing machines, and has to do with ironing machines intended for domestic use and which employ a rotating roll and a cooperating shoe movable toward and away from the roll.

It is customary to dampen articles to be ironed preliminary to the ironing operation. It frequently happens that such articles are considerably damper at certain portions thereof than at others. If these articles be passed through the ironing machine at a uniform rate, there is the possibility that the damper portions of such articles will not be thoroughly dried during the ironing operation. It is an object of my invention to provide simple and efficient means under control of the operator for momentarily stopping rotation of the article while the shoe is in contact with the article, so that the damper portions of the articles being ironed may be subjected to the heat of the shoe, at the discretion of the operator, for sufficient time to assure thorough drying thereof, such means being operable to cause again rotation of the roll while the shoe remains in operative relation to the same.

In the patent to Carl F. Anderson and Rudolph W. Janda, No. 1,656,656, dated January 17, 1928, for Ironing machine, there is disclosed an ironing machine of the character above referred to and which is provided with a box cover hinged to the bed structure of the machine and movable into position to enclose the ironing roll and shoe, this cover, when opened, occupying a position alongside the hot shoe in parallel relation thereto and serving as a guard therefor. In the machine of the patent referred to, means is provided for quickly releasing the shoe and moving it away from the roll, in case of emergency. This means includes a release lever accessible from the front of the machine. A further object of my invention is to provide a release lever of proper length to extend well above the ironing shoe and roll so as to be readily grasped and operated by the operator of the machine and without danger of the operator's arm coming in contact with the hot shoe, this lever being capable of being disposed in a position below the shoe and roll so as not to interfere with positioning over the latter of a box cover the top wall of which, when in closed position, is adjacent the top of the roll and the shoe. A further advantage of the relatively long release lever is that it facilitates operation of the release mechanism with ease and expedition. Further objects and advantages of my invention will appear from the detailed description.

In the drawings:

Figure 1 is a rear view of an ironing machine embodying my invention, with the cover closed and shown in section;

Figure 2 is a section taken substantially on line 5—2 of Figure 1, on an enlarged scale;

Figure 3 is a section taken substantially on line 3—3 of Figure 2, parts being broken away and parts being shown in elevation;

Figure 4 is a section taken substantially on line 10—4 of Figure 2, on a reduced scale;

Figure 5 is a section taken substantially on line 5—5 of Figure 2;

Figure 6 is a fragmentary sectional view taken substantially on line 6—6 of Figure 2; 15

Figure 7 is a section taken substantially on line 7—7 of Figure 3;

Figure 8 is a perspective detail view of the cam member for operating the roll clutch;

Figure 9 is a perspective detail view of the fork member for operating the roll clutch; and

Figure 10 is a section taken substantially on line 10—10 of Figure 1, on an enlarged scale, parts being broken away.

In general, the construction of the machine 25 of the instant application is similar to that of the ironing machine disclosed in my Patent No. 1,867,839, dated July 19, 1932. The machine includes a bed plate 15 having a depending peripheral flange 16 to which are secured the upper ends 30 of supporting legs 17 in a suitable manner, as by nut and bolt means, these legs being formed of sheet metal of suitable gage and of angle cross section. The legs 17 are disposed at the corners of the bed plate, which is of rectangular shape in 35 plan, and may, if desired, be provided at their lower ends with suitable casters such as are disclosed in my patent above identified. Likewise, any suitable means may be provided, if desired, for bracing the legs and maintaining them in 40 proper spaced relation.

Bed plate 15 is provided, adjacent one end thereof, with an opening which accommodates a main gear housing 18, the lower portion of this housing fitting through the opening and extending below the plate. Housing 18 is provided with an outwardly extending flange 19, at the ends and the inner side thereof, this flange seating upon the upper face of bed plate 15 and being secured thereto in a suitable manner, as by means 45 of bolts 20 passing through the flange and the bed plate, nuts (not shown) being screwed onto these bolts. The outer side of the main gear housing is closed by a lower plate 21 suitably secured thereto, as by means of screws, and by 55

an upper plate 22 suitably secured to the housing as by means of screws, one of which is shown at 23, this upper plate being provided, at its lower end, with an inwardly offset lip 24 which engages over the upper edge portion of plate 21.

A worm gear housing 25 is suitably secured, as by means of screws 26 (Figure 1), to the underside of housing 18. The housing 25 is provided with a depending boss (Figure 2) 27 which is 10 suitably bored from its upper end for reception of a shaft 28 rotatably mounted therein. This shaft extends upward through a bearing bushing 29 which fits through a collar 30 integral with and extending upward from bottom wall 31 of 15 housing 18, this collar being concentric with the bore of boss 27. A worm gear 32 is keyed or otherwise suitably secured upon shaft 28 and is rotatably seated upon the upper end of boss 27. Hub 33 of worm gear 32 contacts a flange 34 at the 20 lower end of bushing 29 and acts to hold this bushing against downward movement.

The upper portion of shaft 28 is of reduced and squared cross section, at 35 (Figure 4) and fits into a correspondingly shaped bore in a 25 clutch member 36 secured upon portion 35 of shaft 28 in a suitable manner, as by means of a set screw 37. The upper portion of the bore of clutch member 36 is of enlarged and circular cross section and receives the lower end of the 30 lower reduced and squared portion 38 of a shaft 39 rotatably mounted at its upper portion through a bushing 40 which extends through a relatively thick rib 41 projecting from front wall 42 of the gear housing 18. A dog pointed screw 43 screws 35 into the rib 41, the point of this screw engaging into an annular groove 44 formed in the shaft 39 and holding the latter against endwise movement, this screw also passing through the bushing 40 and holding the latter in the rib 41. Shaft 40 is disposed coaxially with shaft 28 and the lower end of bushing 40 contacts a cup washer 45 disposed about shaft 38. An expansion coil spring 46, mounted about shaft 39, is confined between washer 45 and an angle bearing ring 47 the lower 45 flange of which seats upon the upper face of a flange 48 at the lower end of a clutch member 49 slidably mounted upon squared portion 38 of shaft 39. Clutch member 49 tapers upward and is provided at its upper end with an annular 50 shoulder 50, beneath which the other flange or arm of ring 47 engages, this ring fitting snugly about the body of the clutch member. The clutch members 36 and 49 are of known type and are provided, at their adjacent ends, with teeth 55 which cooperate to establish driving connection between these members when they are in operative relation, in a known manner. The cup washer 45 and the ring 47 permit of the use of a spring of ample size for the purpose intended, 60 and the ring 47 is advantageous as reducing friction and eliminating any tendency to binding of the clutch member 49 on the squared portion 38 of shaft 39.

Spring 46 acts to urge the clutch member 49 65 downward into operative engagement with the lower clutch member 36, thus establishing driving connection between the shafts 28 and 39. A bevel pinion 51 is suitably secured, as by means of a pin 52, on the upper end of shaft 39, above the 70 rib 41. This pinion meshes with a bevel gear 53 suitably secured, as by means of a pin 54, upon the outer end of a roll drive shaft 55. This shaft 55 is rotatably mounted through a boss 56 extending from the inner face of wall 42 of gear 75 housing 18, and through a boss 57 aligned with

boss 56 and extending from the outer face of wall 42. Shaft 55 extends through a tubular supporting arm 58 suitably secured, at its outer end, in boss 57. This arm 58 projects inward over bed plate 15 to within a short distance of 5 the other end thereof, and may contain suitable antifriction bearings for rotatably supporting shaft 55 in arm 58.

A worm shaft 59 is rotatably mounted in the worm gear housing 25, in a suitable manner, and 10 carries a worm 60 rigid therewith, this worm meshing with the worm wheel 32. Shaft 59 extends beyond the inner side of housing 25, beneath bed plate 15, and is connected by a suitable coupling 61 to armature shaft 62 of an electric motor 15 63 supported by brackets 64 suitably secured to the bed plate. Suitable means is provided for connecting the motor into an electric circuit.

Upon closing of the motor circuit, worm wheel 32 drives the shaft 28, the direction of drive of 20 the motor being such that this shaft is driven in a clockwise direction when viewed from above. With the clutch member 49 in its raised or inoperative position, shaft 28 and clutch member 36 25 rotate without effecting rotation of shaft 39. Lowering of the clutch member 36 serves to clutch shaft 39 to shaft 28, these two shafts then becoming, in effect, a single shaft which serves to drive the roll shaft 55 through the pinion 51 and bevel gear 53. Shaft 39 is thus driven, at this 30 time, in a clockwise direction as considered in Figure 7.

Sleeve 58, in conjunction with shaft 55, provides means for rotatably supporting a roll 65 comprising a sheet metal body 66 of cylindrical 35 shape, and suitably arranged reenforcing rings disposed within this body and secured thereto in a suitable manner, as by box welding. One of these rings, designated 67, is disposed adjacent the open end of body 66 and extends inward to 40 within a short distance of the end of sleeve 58. The cylindrical body of the roll is adapted for reception of a suitable length of fabric which may be secured thereon in a suitable manner and is wrapped about the same to form a pad 68 composed of a plurality of layers of the fabric, there being a suitable fabric cover 69 disposed over the pad thus provided.

The end portion of shaft 65 remote from housing 18 is flattened at 70 and fits through a corresponding slot 71 in reenforcing ring 67. The flattened portion 70 of shaft 55 is threaded, and ring 67 is clamped between a nut 72 at the inner face of the ring and a cap nut 73 at the outer face of the ring. The nut 72 abuts the outer 55 face of a ball bearing structure 74 of known type, suitably mounted in the outer end of sleeve 58, and coacts with bevel gear 53 and boss 66 to hold shaft 55 against endwise movement, the two nuts 72 and 73 screwing onto the end portion 70 of 60 shaft 55. The roll is thus mounted for rotation on the axis of arm 58 and when it is desired to remove the roll, this may readily be accomplished by slide lengthwise off of the shaft 55 and arm 58, 65 away from the gear housing 18. To replace the roll, this operation is reversed.

An eccentric structure 75 is mounted for free turning movement about the bearing bushing 29. This structure is provided, at its underside, with 70 a reduced eccentric element 76 which seats upon the upper face of collar 30. An eccentric strap 77 fits above eccentric element 76. This strap is formed at one end of an arm 78 which is provided, at its other end, with a fork 79. This fork 75

receives a block 80 pivotally secured in the fork, on a vertical axis, by a pin 81. This block is also pivotally secured, by a pin 82, to the lower end of an arm 83 secured upon and depending from a shoe operating shaft 84 which is rockably mounted through a bearing sleeve 85 projecting from the inner wall of gear housing 18. This sleeve 85 extends inwardly over the bed plate adjacent thereto and is mounted, adjacent its inner end, in a holding member 86 suitably secured to the bed plate. An arm 87 is loosely mounted upon shaft 84 adjacent the outer face of arm 83 (Figures 2 and 6), and is connected to an ear 88 of arm 83 by means of a pin 89 secured in ear 88 and passing through a slot 90 of arm 87, this slot being concentric with shaft 84. This provides a lost motion connection between arm 87 and shaft 84 which permits of limited rocking movement of the arm independently of the shaft.

20 A fork member 91 is pivotally connected at its lower end, by a headed pin 92, to the other end of arm 87. This fork member is provided with arms 93 which extend beneath the lower flange of angle ring 41. Adjacent its upper end, fork member 91 is provided with a vertical slot 94 which receives enlarged element 43a of screw 43, there being a washer 95 confined between the head of this screw and the outer face of member 91. In this manner, the fork member is slidably mounted on rib 41 of housing 18 for vertical movement. The fork member 91 is further provided, adjacent its upper end, with two fingers 96 disposed at each side thereof and extending therefrom oppositely to the arms 93. A clutch shaft 97 is rockably mounted in housing 18 transversely thereof and adjacent fork member 91. This shaft is flattened at 97a (Figure 3) and fits snugly through correspondingly shaped openings 98 (Figure 8) in the arms of a U-shaped cam member 99. Member 99 embraces fork member 91 and the arms of member 99 are rounded to provide cam surfaces 100. The arms of member 99 are also provided with fingers 101 adjacent the upper ends of the cam surfaces 100 and disposed to contact the outer surface of member 91 when the latter member is in lowered position, as in Figure 8. In this position of member 91, fingers 96 rest upon the upper edges of the arms of member 99, which is horizontal position, and elements 101 contact member 91 adjacent the fingers 96. A suitable handle 102 is secured upon shaft 97, exterior of housing 18 and at the front wall thereof. With shaft 97 in the position illustrated in Figures 2 and 3, fork member 91 is in its lowered position and clutch member 49 is lowered into engagement with clutch member 36 thus driving the roll 65 in the manner previously described. By turning the shaft 97 in an arc of 90° and in a clockwise direction, as viewed in Figure 3, cam surfaces 100 of cam member 99 are caused to exert a camming action on fingers 96 so as to raise the fork structure 91 sufficiently to move clutch member 49 upward into its inoperative position, in which it is out of engagement with clutch member 36, thus stopping the roll 65. In this position of the cam member 99, the pressure exerted by spring 46 is transmitted to the cam member through fingers 96, the line of pressure being substantially in the plane of the axis of shaft 97. This, in conjunction with the friction between the parts, serves to hold the clutch member 49 in its raised position. Turning the shaft 97 in the opposite direction serves to return the clutch member 49 to operative position so as to drive again the roll 65. In this manner,

the roll 65 may be stopped and started at the will of the operator, by suitable turning of handle 102.

Eccentric member 75 is provided with an upwardly projecting flange 105 concentric with shaft 28, the upper face of this member being flat or plane from the flange to the outer edge of the body portion thereof. Member 75 is provided, in the upper face thereof and adjacent flange 105, with a channel 106 of appreciable depth (Figure 5), which receives a tension coil spring 107. One end of this spring is secured, by a pin 108, to member 75. At its other end, spring 106 is provided with an eye 109 which receives a tongue 110 pressed downward from a clutch operating ring 111 which fits about flange 105 and seats upon the upper face of eccentric member 75, this ring forming a closure for the upper end of channel 106. An annular clutch yoke 112 is disposed about flange 105 and seats upon ring 111. This yoke is provided with diametrically disposed notches 113 which receive angularly disposed tabs 114 formed integrally with the ring 111 and projecting upward therefrom, these tabs being outwardly offset relative to the body portion of the ring. A star wheel 115 is disposed within the pocket or recess defined by flange 105 and fits about the squared portion 35 of shaft 28. This star wheel and the yoke 112 are preferably of laminated construction, the elements thereof being suitably secured together, as by riveting. However, the yoke and the star wheel may be otherwise constructed if desired. An annular cover plate 116 is disposed beneath clutch member 36 and seats upon flange 105, to which it is secured by screws 105a, this plate projecting outward beyond this flange and acting to hold the yoke 112 and the star wheel 115 and cooperating parts against upward movement.

Referring more particularly to Figure 4, flange 105 is provided with a slot 117 extending therethrough and of a size to accommodate a clutch disc 118 of a size and shape to fit into the notches 115a of the star wheel 115. Clutch yoke 112 is provided, in its inner edge, with a recess 112a of proper depth to receive the portion of disc 118 which projects beyond flange 105 when this disc is in its outer or inoperative position. This recess is provided with an extension 112b of reduced depth to accommodate the outer portion of the disc 118 when the latter is in its inner or operative position. The spring 107 urges ring 111 in a clockwise direction, as considered in Figure 4.

A trip finger 119 is rockably mounted upon a boss 120 projecting inward from the front wall of gear housing 18. A control rod 121 is slidably mounted in the top of housing 18 and is pivotally connected at its lower end to finger 119. A button 122 is suitably secured upon the upper end of this rod, and an expansion coil spring 123 is mounted about the rod 121 and confined between this button and the bottom of a bore 124 provided in housing 18 to accommodate the button. Spring 123 serves normally to hold the rod 121 raised, thus normally holding the outer end of trip finger 119 depressed and in contact with the upper surface of cam member 75. The finger, when in its normal operative position, is disposed to contact tabs 114 of the ring 111. This serves to hold the yoke 112 in such position that recess 112a thereof is in alignment with slot 117, due to contact of tabs 114 with the end walls of notches 113. At this time the disc 118 is in its outer or inoperative position, and the star wheel 115 is free to turn with shaft 28 independently.

of the eccentric member 75 and other parts associated therewith. At this time, the spring 107 is under tension and tends to move the ring 111 in a clockwise direction, as viewed from above, 5 In Figure 4, the shoe operating shaft 84 has been rocked in a counter-clockwise direction, as considered in Figure 2, into its extreme position, the eccentric member being at this time disposed in its extreme position to the right of shaft 28 and 10 being on dead center with this shaft and pin 81. This provides an eccentric lock which serves effectively to hold the shaft 84 in rocked adjustment.

When it is desired to rock the shaft in the other 15 direction, finger 119 is raised into inoperative position. Spring 107 then turns the ring so as to bring the tabs 114 into contact with the other ends of the notches 113, the spring then acting to turn both the ring 111 and the clutch yoke 112 20 in a clockwise direction as viewed in Figure 4. This movement of yoke 112 moves the disc 118 inward into engagement with star wheel 115 and, the shaft 28 being driven, clutches the eccentric member to the star wheel for rotation therewith. 25 This movement of the yoke 112 serves first to move the disc 118 inward, after which the reduced portion 112b of recess 112a is brought into position to fit about the outer portion of disc 118 thus holding it in its inner or operative position. 30 The eccentric member turns with the star wheel through a half rotation, at which time the other tab 114 of ring 112 contacts trip finger 119, it being understood that this trip finger is returned to its operative position by spring 123 immediately 35 upon release of rod 121. Upon contact of the tab 114 with the trip finger, ring 111 is held against turning movement, yoke 112 continuing to turn with the star wheel until the end walls of notches 113 contact the tabs, at which time 40 the yoke also is held against turning movement. Upon continued turning of the star wheel and the eccentric member, slot 117 is again brought into alignment with recess 112a, at which time disc 118 is forced outward into this recess, by the 45 pressure exerted upon this disc by the star wheel. This returns the parts to their relative positions of Figure 4, except that the disc 118 and associated parts will have been moved through an arc of 180° from the positions of this figure, and the 50 eccentric element will have been turned through an arc of 180°, at which time the shoe operating shaft 84 has been rocked into its extreme position in a clockwise direction as considered in Figure 2. At this time, the eccentric element 55 is again on dead center with the shaft 28 and pin 81, providing an effective locking means for holding shaft 84 in its rocked position.

An arm 125 (Figure 1) is suitably secured, as 60 by means of a pin 126, upon shaft 84 adjacent the holding member 86. This arm extends upward from the shaft and is bifurcated at its upper end for reception of a reduced neck (Figure 10) 127 extending rearward from a head 128 which is secured upon the forward end of an 65 adjusting rod 129. Neck 127 abuts a head 130 at the forward end of a thimble 131, which is also mounted upon the rod 129. This thimble screws through a cruciform member 132 rockably 70 mounted in a shoe carrying arm 133. This arm is bifurcated at its lower end, which straddles arm 125, and is loosely mounted upon shaft 84. At its upper end arm 133 is suitably pivoted to a shoe 134 which cooperates with the ironing roll. 75 This shoe has a concaved forward face to fit

above the roll, when the shoe is in its forward position, and is provided with suitable heating means, preferably electrical means which may be controlled by the same switch which controls the motor.

Rod 129 has a pin and slot connection to thimble 131 for rotating the latter while being slidable therethrough. A knob 135 is suitably secured upon rod 129 at the outer end thereof for rotating the rod in desired direction. The forward 10 face of this knob is recessed and receives one end of an expansion coil spring 136, the other end of which seats in a cup washer 137 mounted about the rod and abutting the rearward end of thimble 131. The means for coupling the arms 15 125 and 133 together is the same as that disclosed in my above identified Patent No. 1,867,839, and need not be described here in greater detail.

With the arms 125 and 133 coupled together, 20 when shaft 84 is rocked in a counter-clockwise direction, as viewed in Figure 2, arm 125 acts through head 128 and rod 129 and associated parts to swing the shoe supporting arm 133 forward thus bringing the shoe into contact with 25 the roll or the work thereon. After this occurs arm 125 moves forward a short distance, placing spring 136 under compression so that the shoe is held to the roll by spring pressure. By rotating rod 129 the effective spring pressure 30 exerted on the shoe can be regulated as required. A release lever 140 is connected to member 132 for rocking the same to couple and uncouple the arms 125 and 133. This lever is provided, at its lower end, with a finger 141 which passes through 35 the upper arm of member 132, this finger being disposed at right angle to the lever.

Arm 132a of member 132 and through which finger 141 passes, is provided with two notches 142 and 143 extending from the opening which 40 receives finger 141, these notches being at the rear face of arm 132a. An expansion coil spring 144 is mounted about finger 141 and confined between the forward face of arm 132a and an abutment in the form of a washer 145 suitably secured 45 upon finger 141 at the forward end thereof. This spring urges lever 141 toward arm 132a so as to hold it in one or the other of the notches 142 and 143. When lever 140 is in notch 142 it is disposed in vertical position and projects 50 well above the shoe 134 and the roll 65. A knob 146 is provided at the upper end of lever 140 for convenience in grasping the same and, in the vertical position of the lever, this knob is disposed a sufficient distance above the hot shoe 55 so as to be readily grasped by the operator from in front of the machine without danger of the operator's arm or hand coming into contact with the hot shoe. The considerable length of lever 60 140 is also of advantage in facilitating operation of the coupling means. When the lever 140 is disposed in the notch 143 it is at an angle of approximately 45° to the horizontal so that knob 146 is below the top of shoe 134, and this shoe and the roll may be enclosed by a box cover 147 65 seating upon the bed plate 15 with the top wall of this cover adjacent the top of the shoe and the roll.

When the machine is being used for ironing, the lever 140 occupies the vertical position shown 70 in dotted lines in Figure 1. By swinging this lever rearward, member 132 is rocked so as to disengage head 128 and neck 127 from arm 125 and swing head 128 upward and rearward into contact with arm 133, thus swinging this latter 75

arm rearward and moving the shoe away from the roll independently of arm 125. This rearward movement of arm 133 is limited by a stop element 86a formed integrally with the holding member 86 and projecting into the path of movement of arm 133. In order to couple the two arms together, lever 140 is swung forward. In the forward movement of this lever head 128 contacts the forward face of the upper end of arm 125 and neck 127 passes into the slotted end thereof, coupling the arms together.

In the normal operation of the machine, cam member 99 is turned to its inoperative position illustrated in Figure 3 thus permitting of vertical movement of fork member 91 in either direction. When the shoe is in its open or inoperative position, pin 89 contacts the wall at the upper end of slot 90 so as to hold arm 87 in raised position, thus holding clutch member 49 in its raised or inoperative position against the tension of spring 46. The shafts 28 and 39 are then decoupled so that the roll is not rotated when the shoe is out of operative relation thereto. Upon movement of the shoe into operative relation to the roll, shaft 84 is rocked in a counter-clockwise direction, as considered in Figure 2, and spring 46 acts to move clutch member 49 downward into engagement with clutch member 36, at which time arm 87 occupies the position illustrated in Figure 2. Accordingly, when the shoe is moved into operative relation to the roll, the shafts 28 and 39 are coupled together to drive the roll 65, in the normal operation of the machine. With the shoe in operative relation to the roll, clutch member 49 may be raised into inoperative position, by turning the clutch control handle 102 in proper direction, at the pleasure of the operator. This permits of momentary stopping of the roll so as to assure thorough drying of relatively damp portion of the article being ironed, in the manner previously described. Also, by retaining the clutch member 49 in its raised or inoperative position, the shoe may be moved toward and away from the roll while the latter remains stationary, by proper operation of the rod 121, for pressing suits and like articles. It will thus be observed that under normal conditions the roll 65 is driven when the shoe is in operative relation to the roll, but rotation of the roll may be prevented at the will of the operator and as conditions require.

The box cover 147 may be constructed and mounted as in my Patent No. 1,867,839, or as in the Anderson and Janda patent, above identified, and the clutch mechanism for controlling operation of the shoe and the means for coupling the shoe supporting arm to the arm which is secured upon the shoe operating shaft are similar to the corresponding means disclosed in my above identified patent and need not be further illustrated nor described here, it sufficing to note that suitable means is provided for operating the shoe shaft 84 and suitable means is provided for establishing operating connection between this shaft and the shoe.

What I claim is:

1. In an ironing machine, an ironing roll, a shoe cooperable therewith, and operating mechanism for said roll and shoe comprising two substantially vertical coaxial shafts disposed in endwise relation, driving means connected to one of said shafts, means connecting the other shaft to the roll, means for moving the shoe to and from the roll, clutch mechanism for connecting said

last mentioned means to said driving means, a clutch for connecting the two shafts together to drive the roll, a member connecting said shoe operating means to said clutch and actuated by operation of the shoe to operate said clutch responsive to movement of said shoe, and means optionally effective for disabling said clutch when the shoe has been moved to the roll and is in cooperating relation thereto.

2. In an ironing machine, an ironing roll, a shoe cooperable therewith, and operating mechanism for said roll and shoe comprising two substantially vertical coaxial shafts disposed in endwise relation, driving means connected to one of said shafts, means connecting the other shaft to the roll, means connecting one of the shafts to the shoe for operating the latter, clutch means normally controlled by said shoe operating means for connecting the two shafts together to drive the roll when said shoe is moved into cooperating relation to said roll, and means for optionally disabling said clutch means when the shoe is in cooperating relation to the roll.

3. In an ironing machine, an ironing roll, a shoe cooperable therewith, and operating mechanism for said roll and shoe comprising a shaft connected to the shoe for moving the same, an arm rigidly secured to the shaft, a second arm loose on the shaft and having a lost motion connection with the first arm, driving means, a clutch for connecting the roll to the driving means, means connecting said second arm to the clutch, means for connecting and disconnecting said first arm to and from said driving means, the lost motion connection between the arms permitting operation of said connecting and disconnecting means independently of said clutch, and means for optionally disabling the clutch when the shoe is in cooperating relation to said roll.

4. In an ironing machine, an ironing roll, a cooperating shoe movable to and from the roll, two substantially vertical coaxial shafts disposed in endwise relation, means for driving one of said shafts, driving connections between the other shaft and said roll, clutch means for establishing and disestablishing driving connection between said two shafts, operating connections between said one shaft and the shoe for moving the latter to and from said roll, means normally operative for enabling and disabling said clutch means in accordance with movement of the shoe to and from the roll, and means for disabling and enabling said clutch means at the will of the operator when said shoe is in cooperating relation to said roll.

5. In an ironing machine, an ironing roll, a cooperating shoe movable to and from the roll, a vertical drive shaft, a vertical driven shaft disposed in endwise coaxial therewith and having direct driving connection to the roll, a clutch controlling driving connection between said shafts, operating connections between said drive shaft and said shoe for actuating the latter, means normally operable for enabling the clutch when said shoe is moved to said roll, and means operable at the will of the operator for preventing enablement of said clutch in the movement of said shoe to said roll and for enabling and disabling the clutch when the shoe is in cooperating relation to the roll.

6. In an ironing machine, an ironing roll, a cooperating shoe movable to and from the roll, a vertical drive shaft, a vertical driven shaft disposed in endwise coaxial relation to the drive shaft and having direct driving connection to the

roll, a clutch member on the drive shaft, a co-operating clutch member slideable on the driven shaft, operating connections between said drive shaft and said shoe for actuating the latter, a clutch shift member cooperating with the slideable clutch member, normally operable clutch control means connected to said shift member for moving said slideable clutch member into operative and inoperative position in accordance with movement of the shoe to and from the roll, and means operable at the will of the operator for preventing movement of the slideable clutch member into operative position in the movement of the shoe to the roll and for moving said slideable clutch member into inoperative and operative position when said shoe is in cooperating relation to said roll.

7. In an ironing machine, an ironing roll, a cooperating shoe movable to and from the roll, a drive shaft, a driven shaft disposed in endwise coaxial relation to the drive shaft and having driving connection to the roll, a clutch member on the drive shaft, a cooperating clutch member slideable on the driven shaft, a rockably mounted shoe shaft, operating connections between said shoe shaft and said shoe, operating connections between the shoe shaft and said drive shaft, an arm having lost motion connection to the shoe shaft and connected to said slideable clutch member for moving the latter into operative and inoperative position in accordance with movement of the shoe to and from the roll, and means operable at the will of the operator for moving the slideable clutch member into operative and inoperative position when the shoe is in cooperating relation to the roll.

8. In an ironing machine, an ironing roll, a cooperating shoe movable to and from the roll, a drive shaft, a fixed bearing member, a driven shaft rotatably mounted through said member in coaxial endwise relation to the drive shaft and having driving connection to the roll, a clutch member on the drive shaft, a cooperating clutch member slideable on the driven shaft and having a flange and a shoulder spaced apart, a ring member disposed between and to contact said flange and shoulder, an abutment member loose on the driven shaft and abutting said bearing member, a coil spring disposed about the said driven shaft and confined between said ring and said abutment member for yieldingly urging said slideable clutch member into operative position, operating connections between the shoe and the drive shaft, and means operable at will for moving said slideable clutch member into inoperative and operative position when the shoe is in cooperating relation to the roll.

9. In an ironing machine, an ironing roll and a cooperating shoe, a cover positionable to enclose said roll and said shoe, a rockably mounted shoe operating shaft, an arm secured on said shaft, a shoe supporting arm loose on the shaft, means for releasably coupling said arms together comprising a coupling member rockably mounted on

one of the arms, and an operating lever attached to said member and disposable to occupy an operative position and an inoperative position, said shoe being in rear of said roll, the lever when in operative position projecting above the roll and the shoe for a considerable distance and when in inoperative position extending upward a sufficiently less distance to accommodate said cover when the latter is in closed position. 5

10. In an ironing machine, a bed plate, an ironing roll extending over the plate, a cooperating shoe in back of the roll and likewise extending over the plate, a box-like cover positionable upon the bed plate to enclose said roll and shoe, a rockably mounted shoe operating shaft, an arm secured on said shaft, a shoe supporting arm loose on the shaft, means for releasably coupling said arms together comprising a coupling member rockably mounted on one of the arms, and an operating lever attached to said member and disposable to occupy an operative position and an inoperative position, the lever when in operative position projecting above the roll and the shoe for a considerable distance and when in inoperative position extending upward a sufficiently less distance to accommodate said cover when the latter is in closed position. 15 20

11. In an ironing machine, a bed plate, an ironing roll extending over the plate, a cooperating shoe in back of the roll and likewise extending over the plate, a box-like cover positionable upon the bed plate to enclose said roll and shoe, a rockably mounted shoe operating shaft, an arm secured on said shaft, a shoe supporting arm loose on the shaft, means for releasably coupling said arms together comprising a coupling member rockably mounted on said shoe supporting arm, an operating lever pivoted to said member for turning movement on an axis substantially normal to said shoe into operative and inoperative position, and means for releasably holding the lever in either position, said lever when in operative position being substantially perpendicular to the shoe and projecting a considerable distance about the latter and when in inoperative being below the top of the shoe and at an inclination thereto. 30 35 40

12. In an ironing machine, an ironing roll and a cooperating shoe, a rockably mounted shoe operating shaft, an arm secured on said shaft, a shoe supporting arm loose on the shaft, means for releasably coupling said arms together comprising a coupling member rockably mounted on said shoe supporting arm, an operating lever pivoted to said member for turning movement on an axis substantially normal to said shoe into operative and inoperative position, and means for releasably holding the lever in either position, said lever when in operative position being substantially perpendicular to the shoe and projecting a considerable distance above the latter and when in inoperative being below the top of the shoe and at an inclination thereto. 50 55 60
